UNITED STATES PATENT OFFICE.

FOREST O. RIEK, OF RHINELANDER, WISCONSIN.

CONDENSER.

Application filed December 17, 1927. Serial No. 240,817.

This invention relates to a condenser designed primarily as part of a household refrigerating apparatus, one of the objects being to provide a simple and efficient condenser of the coil type having means whereby the superposed coils can be maintained in proper relation to each other without requiring expensive connecting means or providing a structure likely to get out of order.

Another object is to provide a condenser assembly which does not become disarranged by variations in temperature, is very compact, and can be put together readily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a view partly in elevation and partly in section of the complete condenser.

Figure 2 is a top plan view thereof.

Figure 3 is an elevation showing one end portion of the condenser coil, the adjacent parts for holding the convolutions properly assembled being shown in section on the line 3—3, Figure 2.

Referring to the figures by characters of reference 1 designates a tube, preferably of copper bent to form a coil having superposed convolutions indicated at 2 and 3. The convolutions are preferably elongated and the ends and one side of the convolutions are disposed in parallel planes. Furthermore the parallel sides of the convolutions are disposed in staggered relation, the convolutions 2 being extended outwardly from the coil 1 beyond the convolutions 3. The opposite sides of the convolutions, however, are crossed as shown particularly in Figure 2, each convolution 2 at this side being inclined upwardly and outwardly to merge into the next adjoining convolution thereabove at one end of the coil while each convolution 3 is inclined upwardly and outwardly to merge into the next adjoining convolution 2 at the other end thereof.

The coil 1 is supported by a base 4 and

straddling the convolutions at each end of the coil are elongated U-shaped holders 5 supported by the uppermost convolutions and having their free ends loosely mounted within spaced apertures 6 formed in the base 4. 60

A bar 6' is extended longitudinally of the top portion of the coil and is provided at each end with a saddle 7 designed to rest upon the crown portion of the adjacent holder 5. Each saddle is bowed transversely so 65 as to fit snugly upon said crown portion. Adjacent each of the saddles is provided a downwardly offset portion 8 adapted to be engaged by a tie rod 9 one end of which is extended through the base 4 where it is held 70 by a nut 10 or the like. The lowermost convolution of the coil merges into an upwardly extended end portion 11 which is arranged within the coil and extended to a nipple 12 which is secured in the center portion of the 75 bar 6, a suitable coupling 13 being provided for attaching the end of the coil to this nipple. The other end of the tube which is extended from the upper convolution of the coil is preferably bent outwardly as indicated 80 at 14 and has a coupling 15 whereby it may be attached to the adjacent part of the refrigerating unit.

It will be noted that by arranging the holders 5 astride opposed portions of the elongated coil, said portions can be held properly assembled in alinement as shown particularly in Figure 1 and, as the ends of the holders are mounted freely within the openings 6, said holders will not interfere with 90 expansion or contraction of the coil due to changes in temperature. The bar 6' with its saddles 7 constitutes efficient means for holding the convolutions properly clamped together where engaged by the holders and also provides a rigid support for one of the ends of the tube forming the coil. It also holds firmly the upper convolution from which the other end of the tube extends. Consequently there is no danger of the coil 95 becoming disarranged because all of the parts thereof will be held firmly under all conditions.

It will be noted that, as the convolutions are out of alinement except at certain spaced 105 points, the action of the condenser will be rendered more efficient than would otherwise be possible. It will also be noted that the tying rods 9 are located inside of the coil so that it thus becomes possible to reduce to the 110

minimum the maximum dimensions of the condenser.

What is claimed is:

- 5 1. A condenser including a base, a tube bent to provide a coil made up of convolutions having opposed contacting portions, holders straddling said contacting portions extending throughout the length of the coil, and a clamping means bridging the coil and engaging and supported by the holders.
- 10 2. A condenser including a base, a tube bent to provide a coil made up of convolutions having opposed contacting portions, holders straddling said contacting portions extending throughout the length of the coil, and a clamping means bridging the coil and engaging and supported by the holders, said clamping means constituting a support for one end of the coil.
- 15 3. A condenser including a base, a coiled tube extended therefrom, separate holding means straddling the convolutions of the coil and loosely engaging the base, a clamping member engaging and supported by the holding means, and means connecting the clamping means to the base for binding the clamping means upon the holder and pressing together those portions of the convolutions engaged by the holder.
- 20 4. A condenser comprising a tube bent to form a coil made up of elongated convolutions, each convolution having its rounded ends and one side occupying a plane parallel with the rounded ends and corresponding sides of the remaining convolutions, said parallel sides of the convolutions being disposed in staggered relation and the rounded ends of said convolutions being crossed to provide portions disposed in alinement, holders straddling the alining portions of the convolutions, and means for tightening the holders upon said engaged portions of the convolutions to bind them together.
- 25 5. A condenser comprising a tube bent to form a coil made up of elongated convolutions, each convolution having its rounded end and one side occupying a plane parallel with the rounded ends and corresponding sides of the remaining convolutions, said parallel sides of the convolutions being disposed in staggered relation and the rounded ends of said convolutions being crossed to provide portions disposed in alinement, holders straddling the alining portions of the convolutions, and means for tightening the holders upon said engaged portions of the convolutions to bind them together, said means including a base at one end of the coil, a clamping member bridging the coil and engaging the holders, and adjustable tying means between the base and clamping means.
- 30 6. In a condenser a base, a tube providing a coil including convolutions having spaced portions crossed and contacting, said convolutions being staggered at one side and crossed

at the other side, and means for binding together the contacting end portions of the convolutions.

7. In a condenser a base, a tube providing a coil including convolutions having spaced portions crossed and contacting, said convolutions being staggered at one side and crossed at the other side, and means for binding together the contacting end portions of the convolutions, said means including a base at one end of the coil, a bar bridging the bar at its other end, holders straddling the contacting portions of the convolutions and loosely engaging the base, said holders having intermediate crown portions engaging one end of the coil, saddles carried by the bar embracing and fitting snugly upon the crown portions of the holders, and adjustable tying means connecting the bar to the base.

8. A condenser including a coil formed of a tube, all of the convolutions of the coil crossing each other at spaced points to provide spaced alining portions extending longitudinally of the coil, the remaining portions of the convolutions being out of alinement.

9. In a condenser a coiled tube providing superposed convolutions, said convolutions being elongated to provide opposed rounded portions and opposed side portions, one side portion and the rounded end portions of each convolution being disposed in a plane parallel with the corresponding side portions and the rounded end portions of the remaining convolutions of the coil, the other side portions of the convolutions being crossed and inclined.

10. In a condenser a coiled tube providing superposed convolutions, said convolutions being elongated to provide opposed rounded portions and opposed side portions, one side portion and the rounded end portions of each convolution being disposed in a plane parallel with the corresponding side portions and the rounded end portions of the remaining convolutions of the coil, the other side portions of the convolutions being crossed and inclined, the rounded end portions of the convolutions being crossed to provide spaced alining portions extending longitudinally of the coil, and means for binding said spaced alining portions of the convolutions together.

11. In a condenser a coiled tube providing superposed convolutions, said convolutions being elongated to provide opposed rounded portions and opposed side portions, one side portion and the rounded end portions of each convolution being disposed in a plane parallel with the corresponding side portions and the rounded end portions of the remaining convolutions of the coil, the other side portions of the convolutions being crossed and inclined, the rounded end portions of the convolutions being crossed to provide spaced alining portions extending longitudinally of the coil, means for binding said spaced alining

portions of the convolutions together, said means including a bar bridging one end of the coil, means at the ends thereof for exerting a pressure against alining portions of the convolutions, a base at the other end of the coil, and means for tying the bar to the base.

12. In a condenser a coiled tube providing superposed convolutions, said convolutions being elongated to provide opposed rounded portions and opposed side portions, one side portion and the rounded end portions of each convolution being disposed in a plane parallel with the corresponding side portions and the rounded end portions of the remaining convolutions of the coil, the other side portions of the convolutions being crossed and inclined, the rounded end portions of the convolutions being crossed to provide spaced alining portions extending longitudinally of the coil, means for binding said spaced alining portions of the convolutions together, said means including a holder straddling the alining portions of the convolutions and extending longitudinally of the coil, a base loosely engaged by one end of each holder, a bar bridging the coil, means at the ends of the bar for engaging the holder, and means connecting the bar to the base for binding said bar upon the holder and for binding together those portions of the convolutions straddled by the holder.

13. In a condenser a coiled tube providing superposed convolutions, said convolutions being elongated to provide opposed rounded portions and opposed side portions, one side portion and the rounded end portions of each convolution being disposed in a plane parallel with the corresponding side portions and the rounded end portions of the remaining convolutions of the coil, the other side portions of the convolutions being crossed and inclined, the rounded end portions of the convolutions being crossed to provide spaced alining portions extending longitudinally of the coil, means for binding said spaced alining portions of the convolutions together, said means including a holder straddling the alining portions of the convolutions and extending longitudinally of the coil, a base loosely engaged by one end of each holder, a bar bridging the coil, means at the ends of the bar for engaging the holder, and means connecting the bar to the base for binding said bar upon the holder and for binding together those portions of the convolutions straddled by the holder, said means being located within the coil, and a connection between one end of the tube and the bar.

In testimony that I claim the foregoing as my own, I have hereto affixed my signature.

FOREST O. RIEK.
